(57) **CLAIM**

The ornamental design for a wrist brace, as shown and described.

DESCRIPTION

FIG. 1 is a perspective view of a wrist brace showing the new design;

FIG. 2 is a bottom view thereof;

FIG. 3 is a top view thereof;

FIG. 4 is a side view thereof;

FIG. 5 is an opposite side view thereof;

FIG. 6 is an edge view thereof; and,

FIG. 7 is an opposite edge view thereof.

The broken lines illustrate portions of the wrist brace which form no part of the claimed design.
